P. WASHBURN, H. G. O. WHITE & G. A. COPELAND.
COFFIN.

No. 11,185.

Patented June 27, 1854.

UNITED STATES PATENT OFFICE.

PHILO WASHBURN, HARRISON G. O. WHITE, AND GEORGE A. COPELAND, OF TAUNTON,
MASSACHUSETTS.

COFFIN.

Specification of Letters Patent No. 11,185, dated June 27, 1854.

To all whom it may concern:

Be it known that we, PHILO WASHBURN,
HARRISON G. O. WHITE, and GEORGE A.
COPELAND, all of Taunton, in the county
of Bristol and Commonwealth of Massa-
chusetts, have invented a new and Improved
Mode of Constructing Coffins; and we do
hereby declare the following to be a full
and exact description.

10 The nature of our invention consists,
first, in a frame for the head and apparatus
for raising and falling the head; second,
the method of fastening on the top or cover
of the coffin by means of hooks and eyes;
15 and third, the facing or lining the sides
of the lid and the aperture in the top of
the coffin that receives the lid, with metal.

To enable others skilled in the art to
make and use our invention, we will de-
20 scribe the method of construction and op-
eration.

We proceed to construct our coffin in any
of the known forms and affix in the head
or forward part thereof, a frame work (as
25 shown at G Fig. 2 of the accompanying
drawings) upon which the head lining is
made fast and extended. This frame work
is secured to the coffin at the two sides and
upper end by hooks, as at F F F F Fig. 2.
30 At each side of this head frame, between
it and the sides of the coffin are two upright
pieces, the ends of which are seen at I I
Fig. 2. In the lower part of these uprights
there is cut a slot in which the bar or head
35 cushion support (O Fig. 5) moves. Upon
the upper side of this bar is the head cush-
ion as shown at P Fig. 5. This bar with
the head cushion attached is operated upon
by means of the tapes or straps (s s Fig. 5)
40 and after being raised or lowered to the
desired position, is held there by securing
these straps to pins upon the inside of the
coffin as at a a Fig. 4 or f Fig. 7. The
slots and bar are so arranged as to allow
45 only of an up or down motion to the head
cushion.

The top or cover of the coffin is got out
in the usual manner, except that it is not
pierced for screws, but in lieu thereof hooks,
50 as shown at b b, Figs. 3 and 6, are fastened
to the under side of the cover; when the
cover is placed upon the coffin these hooks
enter corresponding eyes upon the interior
of the coffin; these eyes are shown at E E E

E Fig. 2; in the drawing, two of them are 55
attached to the coffin and the opposite two
detached. Upon the under side of the cover,
at each side thereof, near the head or up-
per end, there is also attached an eye, as
at d d Figs. 3 and 6; these eyes receive the 60
thumb screws or pins J J Fig. 2, and thus
fasten the top firmly upon the coffin.

The lid or that portion of the top that
is opened to view the face of the occupant
corresponds somewhat in shape to that of 65
the frame upon which the head lining is
fixed. It moves upon hinges and is fastened
by a catch or latch. A portion of the top
with the lid raised is shown in Fig. 3. The
edges of this lid and of the aperture into 70
which it fits, are faced or edged with metal,
thereby making a better finish and more
firmly securing the lining upon the under
side of the lid.

The advantages which we consider are to 75
be derived from a use of these improve-
ments are:—the better adaptation of the
head lining to the general outline of the
head; the facility with which the head may
be raised or lowered and thus brought to 80
its proper position; the reduction in expense
attendant upon the fastening of the cover
to the coffin; the better securing of the lin-
ing of the lid; and the improved and neat
appearance of both cover and lid. 85

What we claim as our invention and wish
to secure by Letters Patent, is,—

1. A movable and adaptable head frame,
round or otherwise, consisting of the fol-
lowing parts, viz: the head frame G, the 90
bar O, the uprights I I, the head cushion
P, the straps S S; and the hooks F F F, as
represented in the accompanying drawings;

2. The method by which the cover is se-
cured to the coffin, viz: the eyes E E E E, 95
the hooks b b, the eyes d d and the thumb
screws or pins J J, as represented in the
drawings;

3. The facing of the edges of the lid and
its corresponding aperture with metal; all 100
for the purpose and in the manner sub-
stantially as herein described.

PHILO WASHBURN.

H. G. O. WHITE.

GEORGE A. COPELAND.
